UNITED STATES PATENT OFFICE

135,402

DESIGN FOR A SHIP HULL

Henry J. Sullivan, Duluth, Minn.

Application August 31, 1942, Serial No. 108,089

Term of patent 7 years

To all whom it may concern:

Be it known that I, Henry J. Sullivan, a citizen of the United States, residing at Duluth, in the county of St. Louis and State of Minnesota, have invented a new, original, and ornamental Design for a Ship Hull, of which the following is a specification, reference being had to the accompanying drawing, forming part thereof.

In the drawing:

Fig. 1 is a side elevational view of a ship hull showing my new design;

Fig. 2 is a top plan view; and

Fig. 3 is a diagrammatic outline of a sectional view taken on the line 3—3 of Fig. 2.

The characteristic features of the ship hull of my design reside in the sponson portions shown in full lines in the drawing.

I claim:

The ornamental design for a ship hull, as shown.

HENRY J. SULLIVAN.
